US00D565722S

(12) **United States Design Patent** (10) **Patent No.:** **US D565,722 S**
(45) **Date of Patent:** **** Apr. 1, 2008**

(54) **VENTILATION GRILLE**

(75) Inventors: **Jesse A. Hollingsworth**, West Bend, WI (US); **Corey Scott Jacak**, Kewaskum, WI (US); **Mirko Zakula**, New Berlin, WI (US); **Hyunchul Kim**, Chicago, IL (US)

(73) Assignee: **Broan-NuTone LLC**, Hartford, WI (US)

(**) Term: **14 Years**

(21) Appl. No.: **29/273,065**

(22) Filed: **Feb. 26, 2007**

(51) **LOC (8) Cl.** **23-04**

(52) **U.S. Cl.** **D23/388**

(58) **Field of Classification Search** D23/388-393, D23/342, 366, 356, 385, 370, 371, 351, 354, D23/386, 335; 454/309, 275-277, 284, 287-289; D26/118, 72, 59, 152; D14/230

See application file for complete search history.

(57) **CLAIM**

The ornamental design for a ventilation grille, as shown and described.

DESCRIPTION

FIG. 1 is a perspective view of the ventilation grille.

FIG. 2 is bottom view thereof;

FIG. 3 is a left side view thereof;

FIG. 4 is a right side view thereof;

FIG. 5 is a front view thereof; and,

FIG. 6 is a rear view thereof.

The broken line showing of parts of the drawings depicts use and environment and forms no part of the claimed design.

1 Claim, 4 Drawing Sheets
